UNITED STATES PATENT OFFICE.

FRANK K. HOBBS, OF GUYMON, OKLAHOMA.

CLAMP.

1,394,413.

Specification of Letters Patent.

Patented Oct. 18, 1921.

Application filed November 9, 1920. Serial No. 422,909.

To all whom it may concern:

Be it known that I, FRANK K. HOBBS, a citizen of the United States, residing at Guymon, in the county of Texas and State 5 of Oklahoma, have invented new and useful Improvements in Clamps, of which the following is a specification.

This invention comprehends the provision of a machine for elevating and lowering 10 pipes, sucker rods and the like, and has for its object a construction which can be conveniently associated with the pipe or rod to be moved and operated in a very easy manner for the purpose intended.

15 More specifically stated, the invention embodies a sectional frame, the respective sections being hingedly connected together and each supporting a pair of rollers, the rollers of one section coöperating with the rollers of 20 the other section to grip the pipe or rod to be moved, the rollers being connected together by gears so that they may be readily and easily rotated for the purpose intended.

25 In carrying out the invention I also equip the respective sections of the frame with a sectional clamp which can be readily and conveniently associated with a pipe upon which the frame is mounted when used for extracting or removing sucker rods or the 30 like.

The nature and advantages of the invention will be better understood when the following detail description is read in connection with the accompanying drawings, the 35 invention residing in the construction, combination and arrangement of parts as claimed.

In the drawings forming part of this application, like numerals of reference indicate 40 similar parts in the several views and wherein:—

Figure 1 represents a plan view of the device.

Fig. 2 a side elevation.

45 Fig. 3, a sectional side elevation through line 3, 3 Fig. 2.

Fig. 4 represents a sectional side elevation at right angles to Fig. 3.

Fig. 5 a plan view of the clamp.

50 The machine forming the subject matter of my invention comprises a sectional frame, the respective sections being indicated at 10 and 11 and hingedly connected, as at 12. The sections are designed to unitedly define 55 a box-like member when the sections are connected together, the sections being held in

this position by means of a latch 12. Journaled between the side members 13 of each section are spaced upper and lower rollers 14 and 15 respectively, the rollers 14 of the 60 respective sections operating in one pair while the rollers 15 of the said sections operate as another pair when the sections of the frame are secured together for use. These upper and lower pairs of rollers serve 65 to grip between them the rod or pipe which is adapted to be moved, and in order that pipes of different diameters may be accommodated between the rollers, the rollers in the section 11 of the frame are mounted for 70 yielding movement toward and away from the rollers of the section 10. Fixed upon the shaft of each roller and at the opposite end of the latter are gears 16, while journaled upon the parallel sides of each section 75 of the frame are relatively small cog wheels 17 which are arranged between the rollers of said section to mesh with the gears 16 thereof. When the sections of the frame are associated for use, the gears 16 of the 80 upper rollers mesh, while the gears 16 of the lower rollers mesh so that all of the rollers are rotated in unison upon turning of the crank handle 18 associated with the roller 14 of the section 10. By reason of this construction, the machine can be conveniently 85 associated with pipes or rods of different diameters and the latter effectively gripped for the purposes set forth. Carried by each of the sections 10 and 11 of the frame is a 90 semi-circular member 20, these members unitedly defining a clamp to embrace a pipe for supporting the machine while the sucker rod or the like is being extracted through the instrumentality of the rollers 14 and 15. 95 The members 20 of said clamp are secured together in any suitable manner, such as at 22.

While it is believed that from the foregoing description, the nature and advantages of the invention will be readily apparent, I desire to have it understood that I do not limit myself to what is herein shown and described and that such changes may be resorted to when desired as fall within the 105 scope of what is claimed.

What I claim is:—

1. A machine of the class described comprising a sectional frame, said sections being hingedly connected together, upper and 110 lower rollers journaled in each section, the upper and lower rollers of the respective

sections being geared together and operating in pairs, means whereby all of said rollers are rotated in unison, and means for holding said sections of the frame operatively associated.

2. A machine of the class described comprising a sectional frame, the sections of said frame being hingedly connected together, upper and lower rollers journaled 10 in each section, gears arranged at the opposite ends of each roller, cog wheels interposed between the rollers and meshing with said gears, the upper and lower rollers of the respective sections operating in pairs 15 and having their respective gears meshing with each other, means for rotating all of

said rollers in unison, and means for holding the sections of the frame connected together.

3. A machine of the class described comprising a sectional frame, said sections being hingedly connected together, upper and lower rollers journaled in each section, said upper and lower rollers of the respective sections operating in pairs, means whereby 20 all of said rollers are rotated in unison, a semi-circular member carried by each of the frame sections, said members unitedly defining a clamp, and means for holding said members together, for the purpose specified. 25

In testimony whereof I affix my signature.

FRANK K. HOBBS.
